Primary Examiner—James Gandy*Assistant Examiner*—Linda Brooks*Attorney, Agent, or Firm*—Amster, Rothstein & Ebenstein[57] **CLAIM**

The ornamental design for a display rack, as shown and described.

DESCRIPTION

FIG. 1 is a top plan view of a display rack showing my new design;

FIG. 2 is a bottom plan view thereof;

FIG. 3 is a side elevational view thereof, taken from the left side;

FIG. 4A is an enlarged fragmentary isometric view thereof of the top left side at the front end;

FIG. 4B is an enlarged fragmentary isometric view thereof of the top left side at the center portion;

FIG. 4C is an enlarged fragmentary isometric view thereof of the top left side at the rear end;

FIG. 5A is an enlarged fragmentary isometric view thereof of the bottom right side at the front end;

FIG. 5B is an enlarged fragmentary isometric view thereof of the bottom right side at the center portion;

FIG. 5C is an enlarged fragmentary isometric view thereof of the bottom right side at the rear end;

FIG. 6A is an enlarged fragmentary top plan view of the front end;

FIG. 6B is an enlarged fragmentary top plan view of the center portion;

FIG. 6C is an enlarged fragmentary top plan view of the rear end;

FIG. 7A is a bottom plan view of FIG. 6A.

FIG. 7B is a bottom plan view of FIG. 6B; and,

FIG. 7C is a bottom plan view of FIG. 6C.
